UNITED STATES PATENT OFFICE

137,373

DESIGN FOR A NECKWEAR DISPLAY RACK

Maynard Davis, Clay Center, Kans.

Application December 2, 1943, Serial No. 111,878

Term of patent 14 years

To all whom it may concern:

Be it known that I, Maynard Davis, a citizen of the United States, residing at Clay Center, in the county of Clay and State of Kansas, have invented a new, original, and ornamental Design for a Neckwear Display Rack, of which the following is a specification, reference being had to the accompanying drawings, forming part thereof.

Figure 1 is a front elevational view of a neckwear display rack, showing my new design; Figure 2 is a side elevational view; Figure 3 is a rear elevational view; and Figure 4 is a top plan view.

I claim:

The ornamental design for a neckwear display rack, as shown.

MAYNARD DAVIS.
